UNITED STATES PATENT OFFICE.

SANTFORD SLUDER, OF COALMONT, INDIANA.

SPRAGGER FOR MINE-CARS.

No. 830,107.

Specification of Letters Patent.

Patented Sept. 4, 1906.

Application filed June 14, 1906. Serial No. 321,723.

To all whom it may concern:

Be it known that I, SANTFORD SLUDER, a citizen of the United States, residing at Coalmont, in the county of Clay and State of Indiana, have invented certain new and useful Improvements in Spraggers for Mine-Cars, of which the following is a specification, reference being had therein to the accompanying drawings.

10 This invention relates to an improvement in mine-car brakes, and more particularly to that type of brake known as a "spragger," in which a sprag bar or bars are adapted to be projected between the spokes of the wheel or 15 wheels of the car to lock the same against movement.

The object of the present invention is the provision of improved mechanism for actuating the sprag-bars.

20 A further object of the invention is the provision of means for locking the sprag-bars in various positions of adjustment.

25 A further object of the invention is the provision of antifriction devices which are secured to the spokes of the car-wheel to facilitate the projection and withdrawal therebetween of the sprag-bars.

Other objects of the invention will be apparent from the detail description herein- 30 after when read in connection with the accompanying drawings, forming a part hereof, wherein a preferable embodiment of my invention is shown and wherein like numerals of reference refer to similar parts in the several views.

35 In the drawings, Figure 1 is a side elevation of a mine-car equipped with my improved spragger. Fig. 2 is a bottom plan view thereof. Fig. 3 is an end view. Fig. 4 is a fragmentary view of one of the wheels of my improved mine-car, showing the antifriction devices secured to the spokes thereof.

40 Referring now more particularly to the drawings, A designates a mining-car, which 45 may be of any suitable construction and which is provided with the supporting-wheels B. Slidably secured in any suitable manner to the under side of the car A on opposite sides thereof are the transversely-movable spraggers C. The spraggers C, which are preferably formed of a single piece of metal, each comprise the sprag-bars c c', the free ends of which extend in proximity to the outer edge of the car-body and are adapted

50 to be projected between the spokes of the front and rear wheels of the car when the spragger is moved outwardly and the intermediate arm c², which terminates in an eye or loop c³. The side bars c are made somewhat longer than the side bars c', so that the spragger may be actuated to engage but one wheel of the car, if desired. Journaled in suitable bearings secured to the sides of the car are the actuating-shafts D, which extend the full length of the car and terminate in the upwardly-extending cranked portions d, which are provided with suitable foot-pieces d', which are accessible to the foot of an operator standing upon the end of the car. The end walls of the cars are provided adjacent 7c their upper edges with handholds E of any suitable construction, accessible to the hand of an operator standing upon the end of the car. The actuating-shafts D are provided intermediate the ends thereof with the upwardly-extending cranked portions d², which are adapted to lie alongside the sides of the car when the actuating-shafts are in their normal positions and the upper ends of which terminate in suitable eyes or loops d³. 80

85 E' designates a pair of links, the outer extremities of which are loosely connected to the eyes d³ of the cranked portions d² of the actuating-shaft D and the eyes c³ of the intermediate arms c² of the spraggers C. The links E' are bent intermediate the ends thereof at substantially right angles, so that when the actuating-shafts D are in their normal position one arm of said links will lie alongside the sides of the car and the other 90 arm of said links will lie alongside the under side of the car-bottom. From this construction it will be seen that an operator standing upon either end of the car may by depressing the foot-pieces d' cause the spraggers C to be 95 moved outwardly to project the extremities of the sprag-bars c and c' thereof between the spokes of the wheels B. The actuating-shafts D are provided adjacent one end thereof with the cranked portions d⁴, which are 100 adapted to lie flat against the sides of the car when the spraggers C are in their retracted position. The actuating-shafts D are maintained in various positions of adjustment by locking devices, each of which comprises a 105 plate F, the upper end of which is loosely secured to the side of the car by a staple f and the lower end of which is arranged to overlie

the cranked portion d^4 of the actuating-shaft D. The plate F is provided intermediate the ends thereof with an elongated slot f^2 , which is adapted to receive a bolt f^2 , which projects laterally from the side of the car. Interposed 5 between a nut secured on the projecting end of the bolt f^2 and the plate F is a coil-spring f^3 , which serves to normally hold the plate flat against the side of the car, thereby retaining the spraggers in their retracted position. The lower end of the plate F projects 10 below the actuating-shaft D for a slight distance and is beveled upon its inner side.

G designates a spring which is secured to 15 the side of the car and which is provided with an arm which bears against the top of the plate F and serves to normally press the same downwardly. The plate F bears against the cranked portion d^4 of the actuating-shaft D 20 with sufficient strength to hold the same in any position to which it may be adjusted, so that the shaft may be rocked a slight distance only if it is desired to throw but one of the sprag-bars into engagement with the 25 spokes of the wheel. When, however, the cranked portion of the actuating-shaft is moved a sufficient distance by the foot of the operator to throw both of the sprag-bars between the spokes of the front and rear wheels, 30 the cranked portion d^4 will be drawn out from beneath the plate F, which will at once, owing to the coil-spring f^3 , be thrown inwardly so as to overlie said cranked portion, and thereby prevent the sprag-bars from being accidentally 35 retracted. When the cranked portions d^4 of the actuating-shaft D are elevated to retract the sprag-bars, the cranked portion d^4 of the shaft will contact with the bottom edge of the plate; but as the same is longitudinally 40 movable it will give a sufficient amount to permit said cranked portion to ride therebeneath.

In devices of this character some difficulty 45 has been heretofore experienced in introducing and withdrawing the sprag-bars, owing to the great amount of friction between the same and the spokes of the car-wheel, particularly when the car was heavily loaded. To obviate this difficulty, I provide the spokes 50 of the wheels B on opposite sides thereof with recesses or pockets b , in which are rotatably mounted friction-rollers b' , with which the sprag-bars contact when projected or withdrawn between the spokes of the wheel.

I do not desire to limit myself to the precise form and construction shown in the drawings, as it is obvious that many minor changes 55 might be made thereto without departing from the spirit of the invention.

60 What I claim is—

1. In a brake for mine-cars, a transversely-movable sprag-bar secured to the under side of the car adapted to be projected between the spokes of one of the wheels thereof, an ac-

tuating-shaft journaled in bearings secured 65 to one side of the car and having a crank portion, and a connection between the cranked portion of the actuating-shaft and the sprag-bar.

2. In a brake for mine-cars, a transversely-movable sprag-bar secured to the under side of the car and adapted to be projected between the spokes of one of the wheels of the car, an actuating-shaft adjacent one side of the car and extending longitudinally thereof, 75 said actuating-shaft being provided with a cranked portion intermediate the ends thereof and an actuating-handle at one end thereof, and a link connecting the cranked portion of the actuating-shaft and the sprag-bar. 80

3. In a brake for mine-cars, a transversely-movable sprag-bar secured to the under side of the car and adapted to be projected between the spokes of one of the wheels thereof, an actuating-shaft arranged at one side of the 85 car and extending longitudinally thereof, and a connection between the actuating-shaft and the sprag-bar.

4. In a brake for mine-cars, a transversely-movable sprag-bar secured to the under side 90 of the car and adapted to be projected between the spokes of one of the wheels thereof, an actuating-shaft positioned at one side of the car and extending longitudinally thereof, a connection between the actuating-shaft and 95 the sprag-bar, and means for locking said shaft in various positions of adjustment.

5. In a brake for mining-cars, a transversely-movable sprag-bar secured to the under side 100 of the car and adapted to be projected between the spokes of one of the wheels thereof, an actuating-shaft positioned at one side of the car and extending longitudinally 105 thereof, said actuating-shaft being provided with an offset portion, a connection between the actuating-shaft and the sprag-bar, and a spring-pressed plate secured to one side of the car and arranged to overlie the offset portion of the actuating-shaft.

6. In a brake for mine-cars, a transversely-movable sprag-bar secured to the under side 110 of the car and adapted to be projected between the spokes of one of the wheels thereof, an actuating-shaft extending longitudinally 115 of the car and projecting beyond one end thereof, the projecting end of said shaft being provided with a cranked portion accessible to the foot of an operator standing on the end of the car, and a connection between the actuated shaft and the sprag-bar. 120

7. In a brake for mine-cars, a transversely-movable sprag-bar secured to the under side of the car and adapted to be projected between the spokes of one of the wheels thereof, an actuating-shaft arranged at one side of the 125 car and extending longitudinally thereof, said actuating-shaft having a cranked portion adapted to normally lie alongside the

side of the car, and a link connecting the cranked portion of the actuating-shaft and the sprag-bar.

8. In a brake for mine-cars, a transversely-movable sprag-bar secured to the under side of the car and adapted to be projected between the spokes of one of the wheels thereof, an actuating-shaft for said sprag-bar positioned at one side of the car and having an offset portion, and a longitudinally-movable spring-pressed plate secured to one side of the car and arranged to overly the offset portion of the actuating-shaft.

9. In a brake for mine-cars, a pair of transversely-movable sprag-bars secured to the under side of the car and adapted to be projected between the spokes of the front and rear wheels thereof, a longitudinally-disposed actuating-shaft positioned at one side of the car, and a connection between the actuating-shaft and the sprag-bars.

10. In a brake for mine-cars, a pair of transversely-movable sprag-bars secured to the under side of the car and adapted to be projected between the spokes of the front and rear wheels thereof, a longitudinally-disposed

actuating-shaft positioned at one side of the car and provided with a cranked portion, and a link connecting the cranked portion of the actuating-shaft and the sprag-bars. 30

11. In a device of the character described, a wheel having antifriction devices secured to the spokes thereof, and a sprag-bar adapted to be projected between the spokes of said wheel. 35

12. In a device of the character described, a wheel having antifriction-rollers journaled in the spokes thereof, and a sprag-bar adapted to be projected between the spokes of said wheel. 40

13. In a device of the character described, a wheel having pockets formed in the spokes thereof, antifriction-rollers journaled in said pockets, and a sprag-bar adapted to be projected between the spokes of said wheel. 45

In testimony whereof I affix my signature in presence of two witnesses.

SANTFORD SLUDER.
